UNITED STATES PATENT OFFICE.

GEORGE W. SINGER, OF SOUTH BEND, INDIANA.

SOFA-BED.

1,257,542.

Specification of Letters Patent. Patented Feb. 26, 1918.

Application filed May 10, 1915. Serial No. 27,040.

To all whom it may concern:

Be it known that I, GEORGE W. SINGER, a citizen of the United States, residing at South Bend, in the county of St. Joseph and 5 State of Indiana, have invented certain new and useful Improvements in Sofa-Beds, of which the following is a specification.

The invention relates to an improvement in sofa beds comprehending a structure 10 which may be readily and quickly converted from one use to the other, the extreme simplicity of the construction guarding against possibility of the arrangement tending to inoperativeness.

15 The improved sofa bed involves a case in which the bed proper is concealed when the parts are arranged in sofa form by the back and seat portions of the sofa, the said sofa portions forming in effect the main support 20 for the bed proper when the parts are arranged in bed forming position.

The bed proper is arranged particularly with a view to permitting the usual clothing to be arranged thereon in practically 25 made-up or ready for use condition and secured and held in this condition during the use of the structure as a sofa, thereby permitting the conversion into a bed without the necessity of securing the bed clothing 30 from other compartments or storage spaces.

The invention in the preferred form of details will be described in the following specification, reference being had particularly to the accompanying drawings, in 35 which:

Figure 1 is a perspective view of the structure of the parts arranged in sofa forming relation;

40 Fig. 2 is a similar view with the sofa seat and back turned down to form a support for the bed, the bed proper being shown in inoperative position;

45 Fig. 3 is a perspective view showing the parts arranged in bed forming relation, the springs and clothing being omitted;

Fig. 4 is a section on line 4—4 of Fig. 1;

Fig. 5 is a perspective of the bed proper illustrating particularly the means for securing the bed clothing in place when the 50 bed proper is in inoperative position.

The improved sofa bed is illustrated and involves what may be termed a case 1 including side portions 2, back board 3 and a

top 4 forming a rectangular box like structure open on the forward side. The side 55 boards 2 are, integrally or otherwise constructed to provide forward extensions 5 coincident with the lower portion of the side boards and extending forward approximately the width of the desired sofa seat. The extensions 60 have edge uprights 6 extending there-above and connected by straps 7 extending from their upper edge to the forward edge of the side boards and constituting the sofa arms. The extensions 5 are 65 connected at their forward edges by a strip or section 8 constituting the front wall of the case and being of a height corresponding to the desired height of the sofa seat above the bottom of the case. 70

Hingedly connected at 9 to the upper edge of the case section 8 is the sofa structure involving a seat 10 and a back 11. These parts are rigidly secured together, the seat being preferably hinged on the lower side 75 and at its free edge, so that it may be turned rearwardly to a position between the extensions 5, thereby disposing the seat portion 10 between and coextensive with the extensions and the back upwardly from the seat 80 portion and between the forward edges of the side boards 2. The extensions 5 are provided on their inner side with supporting sections 12 having their upper edges arranged slightly below the similar edges of 85 the extensions, the sections 12 forming a support for the seat when the latter is in sofa forming position. The side boards 2 are provided on their inner sides near their forward edges with bearing straps 13 against 90 which the back 11 bears when the parts are in sofa forming relation, the bearing straps extending throughout the length of the side boards above the extensions 5, except at the extreme upper end, for a purpose which will 95 later appear. The seat and back 10 and 11 of the sofa element are suitably upholstered as at 14, the upholstering preferably occupying the full length of the seat and back. On the inner surface of the side boards 2 at 100 their upper ends are arranged guide strips 15 formed with longitudinally extending channels or grooves 16, and a closing section 17 is adapted to fit between the side boards and provided at each side edge near the upper end with guide pins 18 to slide in grooves 105

15. The closing section 17 is of a height to extend from the upper edge of the back 11 of the sofa element to the top 4 of the case, so that when the parts are in sofa-forming relation, the closing section completes in effect the back extension of a sofa, as clearly illustrated in Fig. 1. The closing section 17 is adapted to be swung upwardly and moved rearwardly beneath the top 4 when 10 the device is to be converted into a bed, the forward edge of the section 17 in such open position being supported upon the upper edges of the bearing strips 13, as will be apparent from Fig. 3.

15. The bed structure comprises a box like element made up of a suitable frame as at 19, the ends of the structure having corner posts 20 to which at one end is secured a hinged foot board 21 and at the opposite 20 end a hinged head board 22, these parts being the usual parts of a bed structure. These parts, both foot board and head board are adapted for folding inwardly over the box-like structure of the bed being so connected 25 that they may be temporarily locked in upright position when desired. The locking means is not illustrated, as any simple form of latching device may answer this purpose. The relatively inner corner post 20 of the 30 bed box, that is, the corner post next the case 1 when the parts are in bed forming position, are extended below the box body for an appreciable distance and pivotally connected to standards 23 secured to the bottom 35 of the case at a point slightly in advance of the forward edges of the side boards 2, as will be apparent from Fig. 4 of the drawings.

40. The disposition of the parts, so far described is such that with the closing section 17 moving into open position that is beneath the top 4 the sofa section will be turned outwardly so that the free edge of the back 11 rests upon the supporting surface coincident with the bottom of the case, while the 45 rear surface of the seat section 10 extends outwardly in the plane of the upper edge of the forward wall 8 of the case. The bed box or body may be then turned outwardly 50 so that its outer portion rests squarely upon the seat portion 10 of the sofa section, the inner edge of the bed box being supported from the standards 23. Springs 24 are preferably secured to the bottom of the case in a 55 position to receive the inner side of the bed box when the latter is turned into inoperative or folded position, thus supporting the same and maintaining it disposed in the relatively forward portion of the case, as 60 clearly shown in Fig. 4.

As an important feature of the present invention, attention is directed to Fig. 5 wherein is shown a means of holding the removable parts of the bed in made-up relation 65 when the bed is folded within the case. As

previously stated the head and foot boards of the box are foldable inwardly and they are each provided near their upper edge with appropriate openings 25 to which straps 26 are connected having their meeting ends arranged for the usual buckle connection as at 27. The bed clothing and springs or other supporting elements indicated generally at 28 being properly arranged in the box body and the bed clothing made up ready for the use of the bed, the head board and foot board are turned down in the positions indicated in Fig. 5 and the straps applied as noted. The box body may be then turned into inoperative or 80 folded position without in any way disturbing the condition of such body so that when it is desired to use the article as a bed and the parts are otherwise arranged in appropriate relation, all that is necessary is to disconnect the straps, turn up the foot board and head board and the bed is completely 85 ready. This is important as it avoids the objection of the features of making provision for carrying the bed clothing in a different storage space and making up the bed each and every time the conversion is made. 90

That portion of the case rearwardly of the bed box when the latter is in folded relation is provided with hinged arms 29 and 95 a shelf 30 which may be used as clothing supports or for any other desired purpose of a temporary storage character at any and all times.

In connection with the improved structure, a salient feature resides in the extreme simplicity of the parts, and the entire absence of complication due to a very few parts. This avoids the possibility of inoperativeness incident to the usual complication of articles of this character, and is particularly advantageous as sofa beds are desirable only in the ease and simplicity in which they may be converted and in connection with a complete sanitary arrangement, the latter being gained in the present structure by the fact that a bed as an entirety is completely spaced from all sections of the case proper so that a complete circulation of air is had therearound while 100 the sofa section is at no time completely concealed so far as sanitation is concerned. Furthermore all parts are readily and conveniently accessible whenever repair or removal is necessary. 110

115. What is claimed is:

1. A sofa bed involving a case open in the front thereof, a sofa section comprising a relatively fixed back and seat portion movably connected with the case and adapted to 120 close a portion of the opening in the front thereof, a disappearing closing section adapted to complete the closure of said opening. 125

2. A sofa bed involving a case open in the 130

front, a sofa section comprising a relatively fixed back and seat portion, the back being adapted to close a portion of the opening in the front of the case, a bed section normally housed within the case and movable wholly through the opening in the front of the case, and a disappearing section adapted to close that portion of the opening in the

front of the case not closed by the back of the sofa section.

In testimony whereof I affix my signature in presence of two witnesses.

GEORGE W. SINGER.

Witnesses:

LELA W. COOK,
GEORGE J. OTTSCH.
